UNITED STATES PATENT OFFICE.

NATHAN W. CRANDALL, OF HARTFORD, CONNECTICUT, ASSIGNOR TO THE PERKINS CORPORATION, OF HARTFORD, CONNECTICUT, A CORPORATION OF CONNECTICUT.

ELECTRIC-SWITCH BASE.

No. 838,171.

Specification of Letters Patent.

Patented Dec. 11, 1906.

Application filed February 27, 1906. Serial No. 303,284.

To all whom it may concern:

Be it known that I, NATHAN W. CRANDALL, a citizen of the United States, residing at Hartford, in the county of Hartford and State of Connecticut, have invented a new and useful Electric-Switch Base, of which the following is a specification.

This invention relates to the construction of the base of a rotary snap electric switch. The bases of these switches are usually formed of porcelain, which is quite brittle. It has heretofore been customary to provide the locking-plate, which is secured to the front face of the base for the purpose of holding the mechanism while the throwing-spring is made tense and for stopping the mechanism when it is snapped for opening and closing the circuits, with a square hub on its back face. This hub is set into a square depression or recess in the base in order to prevent the locking-plate from turning. On account of the unavoidable variations of these recesses, due to the unequal shrinkage of the material during manufacture, it has been necessary to make the square hubs considerably smaller than the recesses they are to occupy—that is, when the switches are made in large quantities it has been necessary to provide a loose fit for the hubs, so that they would always enter the recesses. Under these conditions the locking-plate turns slightly in the recess, so that the four corners only of the square hub engage the walls of the recess, which are not high, and these, affording but small sharp points of contact, gradually chip off and break away the friable material and in a short time, owing to the constant shock incident to the snapping of the mechanisms, ruin the base and render the switch worthless.

The object of this invention is to provide a cheap and strong construction which will eliminate the tendency of the locking-plate to break or chip off the walls of the recess in which it is located under the shocks resulting from the snapping of the switch. This object is attained by providing a base with a central depression and depressions extending outwardly therefrom and securing therein a locking-plate which has stop-shoulders on its front face and arms extending outwardly from its back face, as more particularly hereinafter described.

Figure 1 of the accompanying drawings shows a plan of a rotary snap-switch base 55 constructed according to this invention with the locking-plate omitted. Fig. 2 shows a plan of the same base with the locking-plate secured in position. Fig. 3 shows a section of the base without the locking-plate. Fig. 60 4 shows a section of the base with the locking-plate. Fig. 5 shows a blank from which the locking-plate is formed. Fig. 6 shows a plan of the blank after it has been subjected to the first operation and the stop-shoulders are 65 formed on its upper surface. Fig. 7 shows the completed locking-plate. Fig. 8 shows a section of the completed locking-plate. Fig. 9 shows the locking-plate-holding sleeve, and Fig. 10 shows the nut used for securing the 70 sleeve.

The base 1 is preferably formed circular in outline, with the usual perforations for the passage of circuit-wires and the screws which are used to hold the stationary contacts in place and the base in position on a wall. Through the center of the base is a perforation 2. In the front face of the base about this central perforation is a depression 3, and extending outwardly from this depression 4. These outwardly-extending depressions are preferably deepest at their outer ends.

The locking-plate which is shown is preferably formed from a metallic blank 5. This 85 is preferably first pressed so as to form the locking-shoulders 6 on its front side, and then it is stamped to form the outwardly-projecting arms 7. It is preferred that these arms taper from the stop-shoulders and that the 90 outer ends be bent backwardly.

A sleeve 8 is secured to the locking-plate desirably by extending a reduced portion of the sleeve through a perforation in the plate and expanding the front end. This sleeve is 95 thrust into the perforation through the base, and the plate is located with the outwardly-extending arms in the outwardly-extending depressions in the front face of the base. Then a nut 9 is screwed on the threaded end 100 of the sleeve on the back side of the base for holding the parts from displacement.

The edges of each arm are shown as formed at an angle with each other to insure strength, and while this construction is preferred it is 105 not essential, since the edges may be parallel.

The arms are bent or deflected backwardly at their outer ends for the purpose of giving them a deeper and stronger hold upon the material of which the base is composed, and this of course also insures higher and stronger walls for receiving the shock incident to the snapping of the switch.

The invention claimed is—

1. The combination of an electric-switch base formed of insulating material and having abutments on its front face, and a locking-plate secured to the front face and having stop-shoulders and outwardly-projecting arms engaging and held by said abutments, substantially as specified.
2. The combination of an electric-switch base formed of insulating material having a central perforation and depression with depressions extending outwardly therefrom, and a locking-plate having stop-shoulders and outwardly-projecting arms fitting said depressions in the base, substantially as specified.
3. The combination of an electric-switch base formed of insulating material having a central perforation and depression with depressions extending outwardly therefrom, the outer portions of said depressions being

deeper than the central portion, and a locking-plate having stop-shoulders and outwardly-projecting and backwardly-bent arms fitting said depressions in the base, substantially as specified.

4. The combination of an electric-switch base formed of insulating material and having abutments on its front face, and a locking-plate having stop-shoulders on its front face and outwardly-projecting and backwardly-bent tapering arms extending from its back face, said arms fitting and being held by the said abutments, substantially as specified.

5. The combination of an electric-switch base formed of insulating material and having abutments on its front face, a locking-plate having stop-shoulders and outwardly-projecting arms mounted on said base and engaging said abutments, a central sleeve extending from the locking-plate through the perforation in the base, and a nut on the sleeve back of the base for securing the locking-plate in place, substantially as specified.

NATHAN W. CRANDALL.
